UNITED STATES PATENT OFFICE

164,370

COIN-OPERATED AUTOMATIC
PHONOGRAPH

Jerry C. Koci, Chicago, Ill., assignor to Chicago
Coin Machine Co., Chicago, Ill., a corporation of Illinois

Application January 13, 1951, Serial No. 13,788

Term of patent 7 years

(Cl. D56—4)

To all whom it may concern:

Be it known that I, Jerry C. Koci, a citizen of the United States of America, and a resident of the city of Chicago, in the county of Cook, and State of Illinois, have invented a new, original, and ornamental Design for a Coin-Operated Automatic Phonograph, of which the following is a specification, reference being had to the accompanying drawings forming a part thereof, and in which:

Fig. 1 is a front elevational view of a coin-operated automatic phonograph showing my new design;

Fig. 2 is a top plan view of the same; and

Fig. 3 is a side elevational view thereof, both sides being substantially the same.

The back of the cabinet is plain.

I claim:

The ornamental design for a coin-operated automatic phonograph, as shown and described.

JERRY C. KOCI.
